(57) **CLAIM**

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; and, FIG. 5 is an opposite side view thereof. The even-length broken lines represent stitching that forms no part of the claimed design. The uneven-length broken lines showing the six circular shaped elements represent eyelets that form no part of the claimed design. The uneven-length broken lines depicting the remainder of the shoe form no part of the claimed design.

1 Claim, 5 Drawing Sheets(56)
